UNITED STATES PATENT OFFICE.

HENRY STORJOHANN, OF GARWIN, IOWA.

HOG-OILER.

1,270,234.

Specification of Letters Patent. Patented June 18, 1918.

Application filed July 17, 1917. Serial No. 181,021.

To all whom it may concern:

Be it known that I, HENRY STORJOHANN, a subject of Germany, but have declared my intention of becoming a citizen of the 5 United States, residing at Garwin, in the county of Tama and State of Iowa, have invented certain new and useful Improvements in Hog-Oilers, of which the following is a specification.

10 My invention relates to an improvement in hog-oilers, and appertains more particularly to a structure having two rollers exposing a large surface.

An object of the invention is to provide a 15 hog-oiler which is readily operated by the animal, and in which the rollers used turn in one direction only. A further object of the invention is to provide a trough in which the oil is received, which permits of the utilization of a small amount of oil as compared with the surface of the oiling-rolls. Further objects and advantages will appear in the specification and be pointed out in the claim.

25 In the accompanying drawings, forming a part of the specification:—

Figure 1 is an end view of my oiler;
Fig. 2 is a vertical cross-section; and
Fig. 3 is a top plan view, with the cover

30 removed.

The numeral 1 is a metal base, preferably shaped somewhat like the letter W, and bent to form two troughs 2 and 3. End-pieces 4, 4, are provided, in which are journaled 35 the axles 6, 6, of the rollers 7 and 8. These rollers are fluted longitudinally and are adapted to extend down an appreciable distance into the troughs 2 and 3. The sides of the trough 1 are slightly resilient, and

have affixed thereto pawls 9 and 10 which 40 bear against the sides of the rollers 7 and 8 respectively, and engage the sides of the longitudinal ribs 11 formed on the surfaces of the rolls.

It will be seen that the hog rubbing vertically against the rollers will cause an upward movement thereof, which will bring the surface, which has been immersed in the oil in the troughs, against the sides and back of the animal. As the hog rubs against 50 the oiler, it is permitted to rotate upwardly, but is prevented from reverse movement because of the stops 9 and 10, which act as pawls on the rollers, the longitudinal flutings 11 acting as ratchets for the pawls.

I also preferably provide a roof for the oiler which comprises an extensible upright 55 12 carrying the sheet-metal cover 13. The cover is provided for the purpose of preventing access of rain to the troughs.

The invention which I have made is simple, does not expose any surface for the hog to rub upon except the rollers, is simple of construction, and can be produced at a minimum of cost.

60 I claim:

A hog oiler comprising a base bent to form two troughs, end plates secured thereto, fluted rollers journaled in the end plates, pawls forming extensions for the outer ends 70 of the base plate which engage the flutings of the rollers to prevent their reverse movement, a cover and an extensible upright extending from the central partition between the two troughs to the cover for detachably 75 and adjustably holding the latter.

In testimony whereof I affix my signature.
HENRY STORJOHANN.
